METHOD OF MOLDING

Filed July 1, 1935

FIG. 1

UNITED STATES PATENT OFFICE

2,076,790

METHOD OF MOLDING

Henry B. Myers, Cleveland Heights, Ohio, assignor
to The Ferro Machine & Foundry Company,
Cleveland, Ohio, a corporation of Ohio

Application July 1, 1935, Serial No. 29,231

1 Claim. (Cl. 22—193)

This invention relates to the art of molding, and more particularly to a novel method and apparatus for forming sand molds for the production of cast metal articles.

More specifically, this invention has to do with a novel method and apparatus for forming green sand molds, having one or more undercut recesses or grooves in a wall thereof, for the production of cast metal articles having one or more corresponding projections thereon such as brake drums having annularly extending ridges or fins. Heretofore cast metal brake drums of this form have been provided with the desired ridges or fins by machining grooves in an annular surface of the drum to leave such ribs or fins upstanding. Such machining of the cast metal brake drums has involved considerable additional expense. By my novel method and apparatus, as will be explained more fully hereinafter, the sand mold is formed 20 with one or more undercut recesses or grooves in a wall thereof whereby the desired ridges or fins are cast integral on the surface of the brake drum.

It is therefore an object of the present invention to provide a novel method of molding wherein in the cavity of a green sand mold is extended by forming an undercut recess in a wall thereof.

Another object of the invention is to provide a novel method of molding involving the forming 30 of a green sand mold with a cavity therein having substantially the shape of the body of the casting desired, and forming one or more undercut recesses or grooves in a wall of the cavity to provide the same with extensions corresponding 35 with projections or fins desired on the casting.

Still another object of this invention is to provide a novel method of molding wherein the forming of the undercut grooves or recesses is accomplished by rolling.

40 A further object of this invention is to provide novel molding apparatus embodying a ridged roller and means for causing relative traversing movement between the roller and a wall of the cavity of a sand mold.

45 Still another object of this invention is to provide novel molding apparatus, of the type referred to, embodying means for eccentrically mounting the ridged roller.

50 Other objects and advantages of the invention will be apparent from the following description when taken in conjunction with the accompanying sheet of drawings, wherein

55 Fig. 1 is a top plan view of molding apparatus embodying my invention.

Fig. 2 is a transverse sectional view thereof taken on line 2—2 of Fig. 1.

Fig. 3 is a partial transverse sectional view showing the shape of the mold cavity prior to the forming of the grooves or recesses in the wall 5 thereof, and

Fig. 4 is a partial transverse sectional view taken through a ribbed brake drum produced by a mold formed according to my invention.

More detailed reference will now be made to the accompanying drawing for the purpose of describing my novel method and apparatus for making sand molds. It will be understood, of course, that the apparatus shown in the drawing is to be regarded as illustrative only and that 10 it is subject to variation within the scope of the appended claim.

In accordance with my novel method, as will be explained more in detail hereinafter, I form 20 a green sand mold with a cavity therein corresponding in shape substantially with the body of the metal article to be cast, and then form one or more recesses, for example grooves or the like, in a side wall of the recess to correspond with projections or fins desired on the article. Although 25 the recesses or grooves may be formed in the wall of the mold cavity in various ways, my invention contemplates the forming of these grooves by a rolling operation whereby the grooves are formed by pressing the ridges of a ridged roller into the 30 sand of the mold as relative traversing movement takes place between the roller and the mold.

In Figs. 1 and 2 of the drawing I show novel apparatus for carrying out my method, although 35 it should be understood that the method can be practiced with the aid of various other kinds of apparatus or machinery. As shown in the drawing, my novel apparatus includes a support 10 which is preferably in the form of a metal plate adapted to rest upon the mold box or section 11 40 containing the green sand 12 in which the mold cavity 13 is formed. The plate support 10 may be provided with laterally extending ears 14 corresponding with the ears 14' of the mold section 11 and having openings 15 in which the dowel pins 16 engage. A roller 18 projects from the underside of the plate support 10 and is adapted to extend into the cavity or recess 13 of the mold when the support rests upon the section 11 in the position shown in Fig. 2 of the drawing.

The roller 18 may be formed of metal, or any other suitable material, and has on its outer periphery a plurality of angularly extending ridges or fins 20 corresponding in number, size and cross sectional shape with the ridges or fins desired 50 55

on the cast metal articles to be produced. The ridges or fins may be formed on the roller by machining grooves 21 in the face thereof. The roller 18 cooperates with the side wall 22 of the mold cavity to form a plurality of undercut grooves or recesses 23 in the cavity wall. I find that best results are obtained when the roller 18 is of relatively large diameter, and although the size of the roller may be varied somewhat, it may have a diameter as great, or greater than, the semi-diameter of the mold cavity in which the roller is to operate.

For operatively mounting the roller 18 on the plate support 10, I provide the latter with a swinging arm 25 which carries the roller. The arm 25 may be mounted for swinging or rotary movement relative to the plate support 10 by providing the arm with a shaft or spindle 26 which is rotatable in and extends through a bearing 27 provided on the support. The free end of the arm 25 is provided with a boss or enlargement 28 in which a spindle 29 is rotatably mounted. This spindle projects outwardly from opposite sides of the boss 28 and the projecting portion of the spindle at one side of the boss is in the form of an eccentric 30. The projecting portion of the spindle at the other side of the boss 28 is in the form of a stem 31 upon which a gear 32 is keyed. The roller 18 is rotatably mounted on the eccentric portion 30 of the spindle 29 and may be retained on such eccentric portion as by means of a head 33 formed on the spindle. If desired, a suitable bushing 34 may be interposed between the eccentric portion 30 and the roller 18.

The gear 32 of the spindle 29 meshes with a relatively stationary gear 36 which is connected to the plate support 10 by means of screws 37. The gear 36 has an opening therethrough aligned 40 with the bearing opening 27 so as to accommodate the shaft 26. The shaft 26 may be prevented from dropping downwardly in the bearing 27 by means of a collar 38, which is secured to the shaft above the plate support 10 and serves as a thrust bearing. A hollow cover 39 may be secured to the plate support 10 around the thrust bearing collar 38 to protect the same and to exclude sand and other foreign matter therefrom.

The shaft 26 may be rotated by any suitable power means, for example by means of the hand lever or crank 40 connected to the outer end thereof.

From the arrangement just described it will be seen that when the crank 40 is rotated the shaft 26 will cause the arm 25 to sweep around beneath the plate support 10 and cause the spindle 29 to revolve around the fixed gear 36. Since the gear 32 of the spindle meshes with the fixed gear 36 it will be seen that such revolving of the spindle will cause the spindle to rotate in the boss 28 of the arm 25. The revolving of the arm 25 causes the roller 18 to be moved around the wall of the mold cavity, and the rotation of the spindle 29 and its eccentric portion 30 causes the roller to be alternately pressed against and moved away from the face of the side wall of the mold cavity. The alternate moving of the roller against and away from the side wall of the mold cavity by the eccentric portion 30 as the roller is swung around within the cavity causes the ridges 20 of the roller to press or cut into the sand of the mold with a sweeping orslicking action to form the grooves or recesses 23 therein.

The gears 32 and 36 are so designed that the

relatively fixed gear 36 is of larger pitch diameter and has a greater number of teeth than the gear 32. Because of the larger number of teeth of the fixed gear 36 the revolving of the arm 25 will cause the spindle 29 to rotate somewhat more than two turns during one revolution of the arm 25. Hence by revolving the crank 40 a sufficient number of times the roller 18 will be pressed against the entire perimeter of the side wall of the mold cavity and will form continuous grooves 10 23 of the desired cross sectional shape and depth therein.

In Fig. 4 of the drawing I have shown, by way of example, a cross section through the rim part of a cast metal brake drum 41 having a 15 generally cylindrical body portion 41' with annular ridges or fins 41'' thereon. In carrying out my novel method of making sand molds for producing the brake drums 41 or like articles, a mold cavity is first formed in the mold section 11 by 20 packing the sand 12 around a pattern which corresponds in shape with the cylindrical body portion of the metal article to be produced. The withdrawing of the pattern from the packed sand leaves therein the mold cavity 13 having a generally cylindrical side wall 22, as shown in Fig. 3, in which the grooves 23 are to be formed by the apparatus just described.

By revolving the handle 40, the eccentric portion 30 of the spindle 29 is rotated 90° from the position shown in Fig. 2 to bring the axis of the roller 18 into its closest position to the axis of the shaft 26. With the roller 18 in this position the plate support 10 is applied to the mold section 11 and the roller will enter the mold cavity 13 without scraping against the side wall thereof. After the plate support has been thus applied to the mold section 11 and positioned thereon by the pins 16 engaging in the openings 15, the crank 40 is revolved to cause the roller 18 to traverse the side wall 22 of the mold cavity and form the grooves 23 therein in the manner explained above. After the grooves have been rolled into the wall of the mold cavity the eccentric portion 30 is again brought to a position 90° from that shown in Fig. 2 to disengage the ridges 20 of the roller from the grooves which have been formed in the cavity wall. The plate support 10 can then be lifted from the mold section and the roller 18 thereby withdrawn from the mold cavity without damaging the grooves which have been formed in the cavity wall.

To facilitate the use of the apparatus it may be desirable to provide indicating means for visibly indicating to the operator the position of the eccentric portion 30 of the spindle 29. For this purpose I may provide on the shaft 26 a gear 42 of the same pitch diameter as the relatively fixed gear 36. The gear 42 drives a gear 43 which is of the same pitch diameter as the gear 32. The gear 43 carries an indication, such as a mark or projecting pin 44, which is located on the gear to correspond with the angular position of the offset portion of the eccentric 30. A fixed reference mark, such as a pointer 45, may be located adjacent the gear 43. The gear 43 and the pointer 45 may be conveniently mounted upon a lug or projection 46 extending above the plate support 10. When the pin 44 registers with the pointer 45 the operator knows that the eccentric 30 is then holding the ridges of the roller 18 in the grooves 23 of the wall of the mold cavity. When the pin 44 moves to a position diametrically opposite the pointer the operator knows that the roller has been disengaged from the cavity wall and can be

withdrawn from the mold without damage thereto.

To protect and support the upper edge of the mold cavity during the rolling operation I may provide the plate support 10 with a ring 48 on the underside thereof which has a contact face for engagement with the sand, corresponding in shape with the contour already given to the sand by the pattern around which the sand was packed. Similarly, the bottom wall of the mold cavity may be protected during the rolling operation by a removable plate 49 applied thereto. As shown in Fig. 2, the roller 18 is in close running cooperation with the ring 48 and the plate 49.

If desired, the plate support 10 may be provided with one or more threaded openings 50 to receive lifting devices, such as screw-eyes, to facilitate the handling of the apparatus and the application of the same to the mold sections 11.

From the foregoing description and the accompanying drawing it will now be readily seen that I have provided a novel method of forming green sand molds for the production of cast metal articles having projections thereon such as brake drums having annular ridges or fins. It will be understood further that by my novel method undercut recesses or grooves corresponding with the projections or ridges of the article are formed

in a side wall of the mold cavity by a rolling operation whereby the ridges of a ridged roll are pressed into the sand. It will also be readily understood that I have provided novel apparatus for forming undercut recesses or grooves in a wall of green sand molds whereby articles having projections or fins thereon can be produced more economically than has been possible heretofore by machining the casting.

While I have disclosed the novel method and apparatus of my invention in a somewhat detailed manner, it will be understood, of course, that I do not wish to be limited to the precise steps of procedure and details of construction herein described, but regard my invention as including such changes and modifications as do not constitute a departure from the spirit of the invention and the scope of the appended claim.

Having thus described my invention, I claim:

The method of molding which comprises forming a green sand mold having a substantially cylindrical recess therein, and then swinging a ridged roller around in the recess and alternately moving the roller against and away from the wall of the recess during such swinging and thereby causing the ridges of the roller to be pressed into the wall with a gyratory slicking action.

HENRY B. MYERS.
